UNITED STATES PATENT OFFICE

124,083

DESIGN FOR A TURNING LATHE

Stanley W. Sparks, Norwalk, Conn., assignor to
Sparks-Simplex Machinery Corporation, Nor-
walk, Conn., a corporation of Connecticut

Application October 15, 1940, Serial No. 95,850

Term of patent 14 years

To all whom it may concern:

Be it known that I, Stanley W. Sparks, citizen of the United States, residing at Norwalk, in the county of Fairfield and State of Connecticut, have invented a new, original, and ornamental Design for Turning Lathes, of which the following is a specification, reference being had to the accompanying drawings, forming a part thereof, and in which:

Figure 1 is a front elevational view of a turning lathe embodying my new design;

Fig. 2 is a top plan view thereof;
Fig. 3 is a rear elevational view thereof;
Fig. 4 is an elevational view of the head end thereof; and

Fig. 5 is an elevational view of the tail end thereof.

I claim:

The ornamental design for a turning lathe, as shown.

STANLEY W. SPARKS.
